(57) **CLAIM**

The ornamental design for an infant security strap arrangement and changing aid, as shown and described.

DESCRIPTION

FIG. 1 is a top, left, and front perspective view of an infant security strap arrangement and changing aid according to the present design;

FIG. 2 is a bottom, left, and rear perspective view of an infant security strap arrangement and changing aid according to the present design;

FIG. 3 is a bottom plan view of an infant security strap arrangement and changing aid according to the present design;

FIG. 4 is a top plan view of an infant security strap arrangement and changing aid according to the present design;

FIG. 5 is a rear elevation view of an infant security strap arrangement and changing aid according to the present design;

FIG. 6 is a front elevation view of an infant security strap arrangement and changing aid according to the present design;

FIG. 7 is a top plan view of an infant security strap arrangement and changing aid according to the present design, in use; and,

FIG. 8 is a top, right, and rear perspective view of an infant security strap arrangement and changing aid according to the present design, in use.

The broken lines in the figures depict portions of the infant security strap arrangement and changing aid that form no part of the claimed design. The broken lines in FIGS. 7 and 8 depicting a changing pad represent environmental subject matter that forms no part of the claimed design.

1 Claim, 5 Drawing Sheets
